UNITED STATES PATENT OFFICE.

GEORGE BROXTON, OF PITTSBURGH, PENNSYLVANIA.

SOCKET WRENCH.

Application filed April 29, 1922. Serial No. 557,412.

To all whom it may concern:

Be it known that I, GEORGE BROXTON, a citizen of the United States, residing at Pittsburgh, in the county of Allegheny and State of Pennsylvania, have invented new and useful Improvements in Socket Wrenches, of which the following is a specification.

This invention relates to wrenches, and more particularly to a socket wrench.

One of the main objects of the invention is to provide a wrench of simple construction and operation which is specially adapted for use in restricted spaces and is free of all projections which would interfere with use of the wrench. A further object is to provide a wrench of the character stated which may be quickly assembled or disassembled. Another object is to provide a wrench which may be readily produced at small cost. Further objects will appear from the detailed description.

In the drawings:—

Figure 1 is an elevation of the wrench; Figure 2 is an elevation of the wrench taken in a plane at right angles to Fig. 1; Figure 3 is an end view; Figure 4 is a fragmentary section taken substantially on line 4—4 of Fig. 2.

The wrench includes a shank 1 provided at one end with a head 2 which is diametrically bored to receive an operating rod 3. At the other end of shank 1 there is provided a cylindrical body 4 having inner and outer diametrical bores 5 and 6, respectively, which are disposed in parallel relation. A jaw 7 is slidably mounted in the outer end of body 4 and co-operates with a similar jaw 8 for gripping nuts and similar articles, each of these jaws having its inner surface formed to provide two faces disposed at an angle of 60° for fitting about the corner portions of hexagon nuts. Jaw 7 is further provided with a neck 9 which fits snugly through a slot 10 extending from the outer end of body 4 and communicating with bore 6. At the inner end of neck 9 jaw 7 is provided with a short rack 11 which meshes with the threaded exterior of an adjusting nut 12 mounted in a slot 13 extending through body 4 at right angles to bore 5. Jaw 8 is provided with a neck 14, which operates in slot 10, to the inner end of which is connected a cylindrical element 15 which operates in bore 6, element 15 being connected by a neck 16 to stud 17 disposed at right angles to the

neck, this stud being threaded so as to thread into and out of operating nut 12 which is bored and threaded to receive the stud. By turning nut 12 the jaws 7 and 8 may be readily adjusted toward or away from each other.

Outward movement of the jaws is positively limited by a sleeve 18 which is threaded onto head 4, this sleeve and the head being cut away at opposite points to expose nut 12 and permit ready grasping of the same. As will be noted more clearly from Fig. 3, the outer faces of the jaws are rounded to conform to the curvature of sleeve 18 and these jaws taper away from the head. This provides a very simple and efficient construction by means of which the jaws are effectually braced and all projections beyond body 4 which would interfere with use of the wrench in restricted spaces are prevented. By moving the jaws toward each other so as to be out of contact with sleeve 18, the sleeve may be threaded off of body 4, after which the jaws may be threaded out of the body by turning nut 12 in proper direction. This permits the jaws to be readily removed and replaced when required.

What I claim is:—

1. In a socket wrench, a head provided with two parallel bores extending diametrically of the head, a jaw provided with a rack fitting into one of said bores, a jaw having a stud fitting into the other bore, and a member carried by the head and engaging said stud and rack for adjusting the jaws toward and away from each other by operating said member.

2. In a socket wrench, a head provided with parallel diametrically extending bores, a jaw provided with a rack movable in one of said bores, a second jaw provided with a stud movable in the other bore, and an interiorly and exteriorly threaded member mounted in the head and engaging said stud and the rack for adjusting the jaws toward and away from each other upon rotation of said member.

3. In a socket wrench, a head provided with two diametrically extending parallel bores, said head being further provided with a diametrically extending slot extending from its outer end and communicating with the outer bore, a jaw provided with a neck 110 slidable in said slot and with a rack rigid with the neck and slidable in the outer bore,

a second jaw provided with a neck slidable in the slot and with a threaded stud rigid with the neck and slidable in the inner bore, and an adjusting nut disposed at right angles to the inner bore, said nut being interiorly and exteriorly threaded and engaging with the rack and the stud for adjusting the jaws toward and away from each other.

4. In a socket wrench, a head provided with two diametrically extending parallel bores, said head being further provided with a diametrically extending slot extending from its outer end and communicating with the outer bore, a jaw provided with a neck slidable in said slot and with a rack rigid with the neck and slidable in the outer bore, a second jaw provided with a neck slidable in the slot and with a threaded stud rigid with the neck and slidable in the inner bore, an adjusting nut disposed at right angles to the inner bore, said nut being interiorly and exteriorly threaded and engaging with the rack and the stud for adjusting the jaws toward and away from each other, and a member detachably secured about the body and positively limiting outward movement of the jaws.

5. In a socket wrench, a body provided with two diametrically extending parallel bores, the body being further provided with a diametrical slot extending from its outer end and communicating with the outer bore and with a longitudinally disposed slot intersecting the inner bore, a jaw provided with a neck extending through said slot and with a rack rigid with the neck and slidable in the outer bore, said body being also provided with an inner slot establishing communication between the bores, a second jaw provided with a neck slidable in the outer slot and with an element rigid with the neck and slidable in the outer bore, said second jaw being further provided with a neck slidable in the inner slot and with a threaded stud rigid with the inner neck and operable in the inner bore, and an interiorly and exteriorly threaded adjusting nut mounted in said longitudinally extending slot and in engagement with said rack and said stud for adjusting the jaws toward and away from each other.

In testimony whereof I affix my signature.

GEORGE BROXTON.
